Des. 197,091
Patented Dec. 10, 1963

197,091

BASKET FOR BERRIES OR THE LIKE

Walton B. Crane, Los Angeles, Calif., assignor to Allied Plastics Company, Los Angeles, Calif., a corporation of California

Filed May 15, 1963, Ser. No. 74,891

Term of patent 14 years

(Cl. D58—4)

FIG. 1 is a perspective view of a basket for berries or the like showing my new design;

FIG. 2 is a side elevational view thereof;

FIG. 3 is a horizontal section taken on line 3—3 of FIG. 2; and

FIG. 4 is a detail section taken on broken line 4—4 of FIG. 3.

I claim:

The ornamental design for a basket for berries or the like, substantially as shown.
